UNITED STATES PATENT OFFICE.

ERNEST H. FOSTER, OF NEW YORK, N. Y.

APPARATUS FOR SUPERHEATING STEAM.

1,136,114.

Specification of Letters Patent.

Patented Apr. 20, 1915.

Application filed September 23, 1910. Serial No. 583,341.

To all whom it may concern:

Be it known that I, ERNEST H. FOSTER, a citizen of the United States, residing at New York, county of Richmond, and State of New York, have invented certain new and useful Improvements in Apparatus for Superheating Steam, of which the following is a full, clear, and exact description.

This invention relates to superheating apparatus for steam boilers, more particularly boilers of the type in which upper and lower drums are connected by groups or banks of water-tubes.

The object of the invention is to provide for such boilers improved superheating apparatus which shall afford an adequate degree of superheat, to facilitate drainage of the superheater, to locate the superheater in a convenient part of the boiler setting, particularly in boilers already set, to support the superheater in an effective manner, and to eliminate or minimize danger of injury to the superheater by excessive temperatures.

To these and other ends the invention consists in the novel features and combinations hereinafter described.

The preferred embodiment of the invention is illustrated in the accompanying drawing, and referring now thereto, Figure 1 is a longitudinal section through the boiler and setting, the groups or banks of boiler tubes being indicated diagrammatically. Fig. 2 is a cross-section on line 2—2.

The boiler employed in the present embodiment consists of three upper drums 10, 11, 12, connected by circulating tubes 13, 14, and a lower drum 15 connected to the upper drums by three banks of tubes 16, 17, 18. In front of the first bank of water tubes 18, is the boiler furnace, the roof or arch of the same being shown at 19. Extending downwardly from the middle upper drum 11 and in rear of the middle bank of tubes is a baffle 20, and extending upwardly from the lower drum 15 and in rear of the front and rear, or first and third, banks of tubes are baffles 21, 22, the former being provided near its top with a shelf baffle 23 for the usual purpose.

The superheater, designated generally by 24, is located behind the rear baffle 22, in the

upper part of the boiler setting 25, and consists preferably of an inlet header 26, an outlet header 27, a middle header 28, and upwardly extending U-shaped superheating tubes 29 connecting the inlet and outlet headers to the middle header, as shown. The superheating tubes are preferably of the type described in the patent of L. B. Nutting, No. 921,878. The headers extend preferably across the boiler setting, and serve to support the superheater, thus serving as steam-cooled beams for the purpose. The headers themselves may be conveniently supported by angle irons 30 suitably mounted in the side walls of the setting. At one end the headers are provided with valved drain pipes 31, by which water condensed in the superheater can be drawn off at will.

For the purpose of minimizing friction the union fittings 32, 33, by which the superheater is connected to the steam space of the boiler and to the steam line, are each connected to the respective headers by a plurality of pipes, for example three each, as indicated at 34. Across the front of the superheater is an angle iron 35, serving to prevent forward displacement of the superheater and serving also to support an inclined transverse baffle 36 extending downwardly and rearwardly from the top of the boiler setting behind the boiler drum 10. In the rear wall of the setting, below the superheater, is a door 36^a, which can be opened to afford access to the superheater for cleaning purposes.

The course of the furnace gases through the boiler setting is indicated by the arrows, and it will be seen that the gases, flowing over the top of the rear boiler baffle 22, are deflected downwardly and rearwardly into the collection of superheating tubes by the superheater baffle 36. Flowing thence upwardly, or in the reverse direction, among the tubes the gases enter the stack 37 through the opening 38 in the top of the setting. The course of the gases through the superheater is such as to subject the tubes most effectively to the heat of the gases, thus giving a high degree of superheat in proportion to the temperature of the gases at that point. It will also be observed that in the arrange-

ment illustrated the headers, and the header joints, are a little outside of the direct path of the gases, so that the parts named are not subjected to temperatures which are likely to prove injurious.

As previously stated, the arrangement herein specifically illustrated and described is the preferred form of the invention, but the latter may be embodied in other forms without departing from its proper spirit and scope.

I claim:

1. The combination with a steam boiler having a plurality of upwardly extending banks of water tubes, of a superheater comprising headers and tubes arranged behind the rearmost bank of tubes, a baffle between the superheater and the said rearmost bank of tubes, and extending sufficiently high to protect the headers and joints, and a baffle in front of the superheater and in rear of the first named baffle, extending only far enough down to direct the heated products between the superheater tubes but above the headers for the purposes described.

2. The combination with a steam boiler having a plurality of upwardly extending banks of water tubes, and a setting inclosing the boiler and having at its rear a stack opening for the escape of furnace gases into the stack, of a superheater in the boiler setting and in rear of said stack opening, an upwardly extending baffle between the rearmost bank of tubes and the superheater, and a downwardly extending baffle in front of the said stack opening and in rear of the first named baffle.

3. The combination with a steam boiler having a plurality of upwardly extending banks of water tubes, of a superheater behind the rearmost bank of tubes, a transverse member in front of the superheater to retain the same in position, a downwardly extending baffle arranged in front of the superheater and supported at its lower part by said transverse member, and an upwardly extending baffle in front of the first named baffle and behind the said rearmost bank of tubes.

4. The combination with a steam boiler having a plurality of upwardly extending banks of water tubes, and a setting inclosing the boiler and having in rear of the rearmost bank of tubes a stack opening for the escape of furnace gases into the stack, of a superheater in rear of said stack opening, comprising transverse headers and upwardly extending superheating tubes connected thereto, a baffle extending downwardly and rearwardly toward the superheating tubes from a point in front of the stack opening, and a baffle in front of the superheater and extending upwardly to a point in front of the first named baffle, whereby the furnace

gases will be directed rearwardly and downwardly then upwardly and forwardly through the superheating tubes to the stack opening.

5. The combination with a steam boiler comprising upper and lower drums connected by upwardly extending banks of water tubes, and a setting inclosing the boiler and having behind the rearmost upper drum a stack opening for the escape of furnace gases into the stack, of a superheater in the setting and behind the said stack opening, a baffle extending downwardly and rearwardly from the said rearmost upper drum toward the superheater, and a baffle extending upwardly behind the rearmost bank of tubes and in front of the superheater to a point in front of the first named baffle, whereby the furnace gases will be directed rearwardly and downwardly and then upwardly and forwardly through the superheating tubes to the stack opening.

6. The combination with a steam boiler having a plurality of upwardly extending banks of water tubes, and a setting inclosing the boiler and having behind the rearmost bank of tubes a stack opening for the escape of furnace gases into the stack; of a superheater comprising transverse headers supported at their ends in the side walls of the boiler setting, and superheating tubes connected to the headers and extending upwardly in rear of the said stack opening; a baffle extending downwardly and rearwardly toward the superheating tubes from a point in front of the stack opening; and a baffle in front of the headers and superheating tubes and extending upwardly to a point in front of the first named baffle.

7. The combination with a steam boiler comprising upper and lower drums connected by a plurality of banks of water tubes; and a setting inclosing the boiler and having at its top in rear of the rearmost upper drum a stack opening for the escape of furnace gases into the stack; of a superheater in rear of said stack opening, comprising transverse headers having their ends supported in the side walls of the boiler setting, and upwardly extending U-shaped superheating tubes connected to the headers; a baffle extending upwardly in front of the headers and behind said rearmost bank of tubes; a baffle extending toward the superheating tubes, to a point behind the first named baffle, from a point in front of the stack opening and in rear of the rearmost bank of tubes; and a transverse member in front of the superheater, serving to prevent forward displacement thereof and to support the lower portion of the said downwardly extending baffle.

8. The combination of a boiler comprising upper and lower drums connected by up-

wardly extending banks of water tubes, a setting inclosing the boiler and having in the rear of the rearmost bank of tubes an upwardly and forwardly projecting baffle, a stack opening behind the rearmost bank of tubes, a baffle connected to the top of the boiler and projecting downwardly and rearwardly and located between the aforesaid

baffle and said stack, and superheaters arranged beyond said baffle and said stack. 13

In testimony whereof I affix my signature in the presence of two subscribing witnesses.
